PRISMATIC PANELING FOR LIGHTING FIXTURES AND THE LIKE

Carl X. Meyer, St. Louis County, Mo., assignor to The Emerson Electric Manufacturing Company, St. Louis, Mo., a corporation of Missouri

Filed Sept. 25, 1963, Ser. No. 76,719

Term of patent 14 years

(Cl. D48—16)

FIG. 1

FIG. 1 is a plan view of a portion of lighting fixture paneling showing my new design, it being understood the design unit which is shown in the upper right corner is uniformly repeated in the three additional unfinished design units.

FIG. 2 is an enlarged fragmentary sectional elevational view taken along line 2—2 in FIG. 1;

FIG. 3 is another enlarged fragmentary sectional elevational view taken along line 3—3 in FIG. 1; and

FIG. 4 is another enlarged fragmentary sectional elevational view taken along line 4—4 in FIG. 1.

The paneling may be of indeterminate exterior dimensions.

I claim:

The ornamental design for prismatic paneling for lighting fixtures and the like, substantially as shown and described.
